UNITED STATES PATENT OFFICE

98,097

DESIGN FOR A WALL CABINET

Ralph W. Swanson, Mount Pleasant, Mich.

Application August 3, 1935, Serial No. 57,923

Term of patent 14 years

To all whom it may concern:

Be it known that I, Ralph W. Swanson, a citizen of the United States, residing at Mt. Pleasant, in the county of Isabella and State of Michigan, have invented a new, original, and ornamental Design for a Wall Cabinet, of which the following is a specification, reference being had to the accompanying drawing, forming part thereof.

I claim:—

The ornamental design for a wall cabinet, as shown.

RALPH W. SWANSON.
